UNITED STATES PATENT OFFICE.

JOHN B. GAMBER, OF WASHINGTON, PENNSYLVANIA, ASSIGNOR TO KEYSTONE DEVELOPING COMPANY, OF WASHINGTON, PENNSYLVANIA, A CORPORATION OF PENNSYLVANIA.

POCKET TOILET-CASE

No. 892,846.

Specification of Letters Patent.

Patented June 30, 1908.

Application filed January 13, 1907. Serial No. 362,601.

To all whom it may concern:

Be it known that I, JOHN B. GAMBER, a citizen of the United States of America, residing at Washington, in the county of Washington and State of Pennsylvania, have invented certain new and useful Improvements in Pocket Toilet-Cases, of which the following is a specification, reference being had therein to the accompanying drawing.

10 This invention relates to toilet cases for holding conveniently the toilet implements and articles such as a combined brush and comb and the object thereof is to provide a receptacle not only constituting a case for a toilet article but also embodying in its construction a plurality of mirrors for use when occasion so requires.

Further objects of the invention is to provide a toilet case which shall be simple in construction, efficient in use, strong, durable, and inexpensive to manufacture.

In describing the invention in detail, reference is had to the accompanying drawings which form a part of this invention and in 25 which:

Figure 1 is a perspective view of the pocket toilet case in accordance with this invention. Fig. 2 is a longitudinal sectional view of the same showing a toilet article arranged in the 30 case. Fig. 3 is a plan of the brush and comb, the latter being extended from the body of the brush.

Referring to the drawings in detail, 1 denotes a rectangular receptacle preferably of 35 metal such as aluminum, closed at one end and open at its other end. The open end of the receptacle is provided with a flanged hinged lid 2 formed with a recess 3 in which is adapted to extend a lug 4 carried by the 40 edge of the receptacle. The lug 4 in connection with the recess 3 constitutes a clasp for holding the lid in closed position. The said receptacle has its top and bottom walls depressed or countersunk as at 5 and in each 45 of said depressions is positioned a mirror 6. The mirrors are retained in position through

the medium of frames 7, which are secured to the receptacle. In the receptacle is adapted to fit a brush 8 having a back 9 which is slotted as at 10. Pivotaly-mounted in the slot 10 at one end of the back 9 is a comb 11 having one end formed with a lug 12. The ends of the back 9 of the brush 8 are rounded and the length of the comb with respect to the back is such that the lug 12 will project from one end of the back when the comb is positioned within the back thereby providing means for facilitating the withdrawal of the comb from the back 9. In Fig. 2 the lug 12 is shown projecting past one end of the back 9.

The size of the receptacle is such as to snugly fit in a vest pocket as well as readily carried in a chatelaine bag or similar satchel. The providing of the receptacle with two mirrors makes it convenient to the user, as it is not necessary to turn it around in the hand if the mirror be desired for use.

What I claim and desire to secure by Letters Patent, is:—

A pocket toilet case comprising a rectangular receptacle closed at one end and open at its other end, said receptacle having its top wall formed with a depression in the outer face thereof and its bottom wall formed with a depression, a mirror mounted in each of said depressions, frames for securing the mirrors to the receptacle, a lid hinged to the lower wall of the receptacle and having flanges adapted to fit over the open end of the receptacle, the upper of said flanges having a recess in its upper face, and a lug carried by the top wall of the receptacle near the open end thereof and adapted to engage in said recess for retaining the lid in a closed position.

In testimony whereof I affix my signature in the presence of two witnesses.

JOHN B. GAMBER
